DESIGN FOR A BILLFOLD

Morris Smallman, New York, N. Y.

Application January 20, 1945, Serial No. 117,512

Term of patent 14 years

(Cl. D87—3)

To all whom it may concern:

Be it known that I, Morris Smallman, a citizen of the United States of America, residing in New York, county of New York, and State of New York, have invented a new, original, and ornamental Design for a Billfold, of which the following is a specification, reference being had to the accompanying drawing, forming part thereof.

Fig. 1 is a front view of a billfold showing my new design.

Fig. 2 is a fragmentary view of the left side of the article shown in Fig. 1, with the pass holder in open position. The back of the billfold is substantially plain.

I claim:

The ornamental design for a billfold, substantially as shown and described.

MORRIS SMALLMAN.
